UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

IGNITION DISTRIBUTOR.

Application filed December 26, 1923. Serial No. 682,716.

This invention relates to a distributor for electrical current and as illustrated is particularly adapted for use in the distribution of ignition current to the various cylinders 5 of an internal combustion engine.

The principal object of my invention is to provide a distributor for a multi-cylinder engine, to which the cables may be quickly attached with the least amount of work.

10 It is another object of my invention to provide a distributor which is relatively simple in construction, yet efficient in its operation.

Other objects will be apparent to one 15 skilled in this art after a study of the drawings taken in connection with the specification.

In the drawings:

Figure 1 is a plan view of a distributor 20 with the cover removed,

Figure 2 being the inner part of the cover fitting over the distributor shown in Fig. 1.

Figure 3 is a sectional view on the line 3/3 25 of Fig. 1, but with the cover and other parts in position.

Figure 4 is a sectional view of a somewhat modified form of distributor, along the line 4/4 of Fig. 10.

30 Figure 5 is a plan view of the distributing member shown in Fig. 3.

Figure 6 is a sectional view on the line 6/6 of Fig. 5.

Figure 7 is a plan view of the rotating 35 distributing member shown in Fig. 4.

Figure 8 is a side view of Fig. 7.

Figure 9 is a fragmentary sectional view on the line 9/9 of Fig. 1.

Figure 10 is a fragmentary plan view 40 similar to Fig. 1, but of the distributor block shown in Fig. 4 with the cover removed.

Referring to the details wherein like numbers refer to corresponding parts in the various views, 1 is a supporting member in which a pair of frictionless bearings 2 are positioned for the purpose of carrying an operating shaft 3. In Fig. 4 a plain bearing 4 is used instead of the ball bearings shown 45 in Fig. 3. Carried on the stub shaft 3 is a collar 5, the same being held there in any suitable manner as by nut 6. To the collar 5 is attached a distributing member 7, the same being held to the collar 5 as by screws 50 8, only one being shown in the sectional view,

Fig. 3. The distributing member 7 is of any suitable insulating material and preferably moulded therein, is an insert 9, having a centrally located contact 10. To the insert 9 is attached a main contact terminal 11, as 60 by means of a screw 12.

The support member 1 is fastened to some part of the engine casing as by means of a suitable number of screws 13. Carried on the support member 1 is a block of insulating material 14, which is held to the member 1 in any suitable manner as by screws 15. The block 14 has a number of substantially radially arranged recesses or channels 16, which are deeper toward the edge of the block and slope or taper upward toward the center thereof as is clearly shown in Fig. 3. In the deeper part of each of the channels 16 is positioned a contact 17 shown in the form of a stiletto pin. This pin is securely fastened to a plate 18 and the two together are preferably moulded integral with the block 14. There is an opening through the bottom of each channel and positioned in this opening is an ignition pin 19, which in the form shown is arranged so that it can be riveted to the plate 18 after the block has been moulded. I prefer this arrangement because of the large number of pins 19 projecting downward in opposite direction from the stiletto pins 18, makes the withdrawal of the whole block from the mould difficult, as the lower projecting pins are likely to be bent. Therefore, I have constructed the block so that the ignition pins 19 may be put in as 75 80 85 90 a separate operation.

The channels 16 are of such depth that the high tension electrical cables 20 lying therein will be forced downward over the stiletto pin 17, which thereby makes contact with the conductors 21 and at the same time the cover 22 will press against the upper surface of the cable 20 and hold it securely in position in the channel and over the pin 17. This holding action of the cover on the cables 100 is improved by means of a series of ridges 23 moulded in the cover. The cover in Fig. 3 has a central opening 24 through which all of the cables lying in the channel 16 may pass. In addition, a centrally located cable 25, coming from the ignition coil or an ignition magneto, is attached to an insert 26 through the medium of a wood screw 27, it being understood that the strands of the conductor 21 pass through the hole in the 105 110

insert 26 and spread apart and are gripped by the screw 27. The insert 26 carries a button of conducting material 28, the button being held against the contact 10 by a spring 29.

Where a high tension magneto is used for ignition it is the common practice on aircraft engines to use an auxiliary starting magneto, such as shown in De Lorme Patent 1,360,273 issued November 30, 1920, and in order to carry this auxiliary starting current through the distributor and to the ignition pins 19, I connect a cable 30 coming from the auxiliary source of starting current to one of the studs 31 which is used for holding the cover to the distributor block.

This detail is shown particularly in Fig. 9. A contact 32 is connected to the stud 31, whose position may be indicated by dotted line shown in Fig. 3. The distributor member 7 as shown carries an annular ring 33, which is adapted to cooperate with the contact 32, and the ring 33 is connected by means of a conductor 34 (see Fig. 6), to an ignition pin 35 that is in the same plane with contact 11, but set at an angle trailing behind the main contact 11 (see Fig. 5). The parts 34 and 35 are shown in dotted position in Fig. 3, but at an angle of approximately 180 degrees for the purpose of clarity. The purpose of the trailing brush is to allow the starting ignition current to be applied to one of the working cylinders at a time after the given piston has gone over compression.

In order to prevent the starting ignition current from jumping from the annular ring 33 to any part of the metal support member 1, I provide a barrier 36 which in the form shown in Fig. 3 is an insulating disc, but in Fig. 4 it is the bottom of the distributor block. It will be readily observed that the pin 32 may be placed in the member 7 and the annular ring 33 may be placed in the distributor block as is shown in Fig. 4. In this particular figure the distributor block is made in two sections 37 and 38, the upper section 37 being constructed so that it may be rotated with respect to the lower section 50 and the distributor member 7 for the purpose of adjusting the ignition pins 19 with respect to the main distributor contact 11, after which adjustment has been performed, the section 37 is locked by means of a screw 55 39 passing through one of the studs 31 into engagement with the serrations 40 which may be moulded in the section 37 (see Fig. 10). This adjustment is observed through a peep hole covered by a piece of non-inflammable insulating material, such as mica illustrated by the numeral 41 (Fig. 3).

In the forms shown, the distributor is what is known to the trade as the jump spark type, rather than the wipe contact type.

The cables 20, instead of leaving the distributor from the center in Fig. 4, leave the block radially and the holes 42 through the block 14 for securing the pins 19, are somewhat deeper than in Fig. 3. Also the cable 30 from the starting ignition source of current is attached to the ring 33 in a somewhat different manner than in Fig. 3.

It will be apparent that various changes may be made in the details without departing from the spirit of my invention and the scope of the appended claims.

Having thus described my invention, what I claim is:

1. In an ignition distributor, a support member having an operating shaft positioned therein, a current distributing member rotatably carried by said shaft and having a main distributing contact extending to the center of one face thereof, a distributing block carried on said support member and having radially disposed channels with contacts positioned therein, said contacts having parts extending within the block into co-operative position with said distributing contact, a cover fastened to the block, said cover acting to hold the cables in position on said contact, a central conductor passing through the cover into the block and having means for engaging with said main distributing contact.

2. In an ignition distributor, a support member having an operating shaft positioned therein, a current distributing member rotatably carried by said shaft and having a main distributing contact extending to the center of one face thereof, a distributing block carried on said support member and, having radially disposed channels sloping upward toward the center of the block, contacts positioned in the deeper ends of the channels and having parts extending within the block into co-operative position with said distributing contact, a cover fastened to the block, said channels being of such depth that the cover will engage cables lying therein and hold the cables securely in place on said contacts, said cover having a central opening through which all the cables to said channels will pass, including a cable running to the central part of said block and having means in the block for completing a connection to said main distributing contact.

3. In an ignition distributor, a support member having an operating shaft positioned therein, a current distributing member rotatably carried by said shaft and having a main distributing contact extending to the center of one face thereof, a distributing block carried on said support member and having radially disposed channels sloping upward toward the center of the block, contacts positioned in the deeper ends of the channels and having parts extending within the block into cooperative position with said

- distributing contact, a cover fastened to the block, said cover having a series of annular ridges near the outer periphery of its inner face, said channels being of such depth 5 that cables lying therein will be gripped by the ridges on the cover and held firmly in place on the contacts in said channels, said cover having a central opening through which all the cables to said channels will 10 pass, including a cable running to the central part of said block and having means in the block for completing a connection to said main distributing contact.
4. In an ignition distributor, a support member having an operating shaft positioned therein, a current distributing member rotatably carried by said shaft and having a main distributing contact extending to the center of one face thereof, a distributing 15 block carried on said support member and having radially disposed channels with contacts positioned therein, said contacts having parts extending within the block into co-operative position with said distributing contact, a cover fastened to the block, said cover 20 acting to hold the cables in position on said contact, a central conductor passing through the cover into the block and having means for engaging with said main distributing contact, an auxiliary contact, set in trailing 25 position with reference to the main contact, with a current collecting member in electrical contact therewith but carried on the distributing member near the face opposite to that having the main contact, an auxiliary 30 current contact member carried by the block in position to co-operate with said collector member, and means for shielding the auxiliary current collecting member and its co- 35 operating contact in the block so the auxiliary ignition current will take its proper path.
5. In an ignition distributor, a support member having an operating shaft positioned 40 therein, a current distributing member rotatably carried by said shaft and having a main distributing contact, a distributing block comprising two sections of insulating material, means for fastening said sections to 45 said support member, contacts carried by one of said sections and extending inwardly into co-operation with the distributing member, means carried in part by said fastening means for adjusting the angular position of 50 the contact carrying section with respect to the other section and to the rotatable distributing member, means for connecting electrical cables to said contacts and means for carrying a source of current to said rotatable 55 distributing member.
6. In an ignition distributor, a support member having an operating shaft positioned 60 therein, a current distributing mem-
- ber rotatably carried by said shaft and having a main distributing contact and an auxiliary current distributing contact extending into trailing position with respect to the main contact, also a current collecting member spaced away from the main contact but electrically connected to the trailing contact, 65 a two-section distributing block carried on said support member, contacts carried by the outer of said sections and extending inwardly into co-operation with the distributing member, means for adjusting the angular position of the outer section with respect to the inner section and to the rotatable distributing member, means for connecting electrical cables to said contacts, means for conveying current to the main distributing contact, and means carried by the lower section of the block for conveying auxiliary ignition current to said current collecting member. 70
7. In an ignition distributor, a support member having an operating shaft positioned 75 therein, a current distributing member rotatably carried by said shaft and having a main distributing contact, a two section distributing block carried on said support member and housing the distributing member, 80 said outer section having substantially radially disposed channels with contacts arranged therein, said contacts extending within the block into co-operative relationship with said distributing contact, a cover fastened to the block and acting to hold the cables in position in the channels and on the contacts, means for passing current to said distributor contact, and means for angularly adjusting the outer section of the block with 85 respect to said distributor contact.
8. In an ignition distributor, a support member having an operating shaft positioned 90 therein, a current distributing member rotatably carried by said shaft and having a main distributing contact, a distributing block enclosing said distributing member and carried on said support member and having channels therein for the reception of electrical cables, contacts positioned in said channels and having a connecting member extending through the block into co-operative 95 position with said distributing contact, each of said contacts consisting of a stiletto pin for piercing the cable, a plate and an ignition pin; said ignition pin adapted to be fastened to the plate after the block has been moulded with the plate and stiletto pin in position, a cover fastened to the block and acting to hold the cables in position in the channels and on said contacts and means for 100 passing current to the main distributing contacts.

In testimony whereof, I affix my signature.

EDWARD B. NOWOSIELSKI.
